UNITED STATES PATENT OFFICE.

JACK W. JOHNSON, OF CHICAGO, ILLINOIS, ASSIGNOR TO MCKEEL OIL HEAT COMPANY, OF CHICAGO, ILLINOIS, A CORPORATION OF ILLINOIS.

COMBUSTION APPARATUS.

Application filed July 23, 1923. Serial No. 653,400.

To all whom it may concern:

Be it known that I, JACK W. JOHNSON, a citizen of the United States, residing at Chicago, in the county of Cook and State of Illinois, have invented a new and useful Improvement in Combustion Apparatus, of which the following is a specification.

My invention relates, more particularly, to combustion apparatus for producing heat or illumination from liquid hydrocarbon of any suitable character as the fuel.

Certain of my objects are to provide for the conditioning of the hydrocarbon liquid to the end that it shall be rendered of maximum efficiency in heating and lighting to avoid the formation of free carbon; and to provide a combustion apparatus which, while compact and of small size, shall be capable of producing large volumes of the combustible mixture and by which widely varying volumes of such mixture may be caused to flow to the point of ignition under accurate and minute control and, if desired, the flow be maintained continuously throughout the varying of the volume of the mixture under control.

Referring to the accompanying drawings:

Figure 1 is a plan view of combustion apparatus constructed in accordance with my invention; and Figure 2, an enlarged section taken at the line 2-2 on Fig. 1 and viewed in the direction of the arrow.

As a preface to the following description, it may be stated that my invention, in its broadest aspect as to one phase thereof, involves the subjection of the liquid hydrocarbon, constituting the fuel to be used, together with a carbureting material, as, for example, air, to a suction action and an action operating to force the mixture of the liquid and carbureting material, from the point where suction is exerted, to the point at which the mixture is to be ignited.

Inasmuch as I have devised my invention more particularly for the heat-producing purpose, I have illustrated it in this connection, the particular construction shown comprising a vacuum pump 3, which may be of any desirable construction, but which is preferably of the rotary positive vacuum compression type, this pump being shown as driven by an electric motor 4 mounted on a base 5 supporting the pump 3. The suction-inlet of the pump 3 is shown as connected with a pipe 6 which opens into the outlet

of a carbureter 7, which latter may be of any desirable type to which the liquid hydrocarbon, constituting the fuel, is supplied through a pipe 8, from any suitable source thereof. The carbureter shown is provided with an air-control valve controllable through the medium of a lever 9 as is usual in carbureters, and with a lever 10 connected with the throttle valve (not shown) of the carbureter, in accordance with common practice, this lever being shown as provided with the divergent arms 11 and 12 cooperating with a stop pin 13 on the carbureter.

The compression-outlet of the pump is connected with a pipe 14 which opens into an annular chamber 15 provided in the hollow ring 16 forming a part of the burner; the ring 16 being mounted on a base member 17 which is so shaped as to afford a receptacle 18 below the ring 16 and disposed concentrically thereof, the receptacle 18 communicating with a pipe 19 which opens through the bottom of the receptacle and is provided for a purpose hereinafter described. The bottom wall of the chamber 16, at a point diametrically opposed to the pipe 14, contains a recess 20 into which the lower end of a Venturi tube 21, secured at its upper end in an opening 22 in the top wall of the ring 16, extends, the upper end of the Venturi tube communicating with the lower end of an upwardly-extending pipe 23, the upper extremity of which is of downwardly curved form to discharge downwardly, the burner being provided, directly in vertical line, with the outlet of the pipe 23, and below the latter, with a spreader-plate 24 concentric with the outlet of the pipe 23 and supported on a cross-bar 25 of the base 17, to extend above the ring 16.

In the operation of the apparatus the pump 3 which is rapidly driven by the motor 4, exerts suction on the outlet of the carbureter 7, with the result of causing the liquid hydrocarbon, supplied thereto through the pipe 8, and the carbureting air, to be drawn from the carbureter into the pump from which it is forcibly ejected through the pipe 14 into the chamber 15 and thence through the Venturi tube 21 and tube 23, discharging downwardly from the latter at which the mixture is ignited, the plate 24 serving to deflect the burning gases laterally in all directions. The arrangement of the parts is such, as shown, that the flame-produced by

the burning mixture discharging from the pipe 23 impinges against the ring 16 heating the mixture-contents thereof sufficiently to gasify the same.

5 It will be understood that the apparatus shown serves very effectually to produce an intimate mixture of the liquid hydrocarbon and the carbureting material in its passage to the outlet of the course through which it travels, it being noted that the hydrocarbon and the carbureting material is not only subjected to a mixing action in the carbureter wherein the hydrocarbon is vaporized, but also by a very thorough mixing action 10 produced by the vacuum pump, which action is augmented by further mixing action which takes place before the mixture in gaseous form issues from the pipe 23 and in its passage to which latter the gas is caused to expand in the chamber 15 and also 15 in the Venturi tube 21, the location of the latter relative to the recess 20 insuring against the accumulation, in the chamber 15, of such of the hydrocarbon as may become 20 liquefied therein.

It will be understood from the foregoing that the flow of combustible mixture from the pipe 23 may be accurately controlled, as through the medium of the throttle lever 10, the variations of flow obtainable by the apparatus being of very great range. This feature of the apparatus is of especial 25 importance when the apparatus is used as a heating medium, as, for example, for boilers, furnaces and the like, as a flow of combustible mixture to the point of ignition may be maintained at all times, varied in volume, as desired, and thus the use of a pilot light is avoided.

30 In the use of the apparatus, where temperature control is desired, as for example where the apparatus is used for heating a building, any suitable thermostatic controlling means may be provided, the construction shown involving such a means for controlling the flow of combustible mixture to the pipe 23 through the medium of the throttle lever 10. The thermostatic means shown comprise a lever 26 pivoted at one 35 end to the end of the throttle lever 10 opposite that provided with the legs 12 and pivotally connected at its opposite end, to a crank pin 27 secured to a disk 28 mounted on a shaft 29 journaled in a case 30 which latter may contain any suitable mechanism 40 for rotating the disk 28 and thereby varying

the opening of the valve controlled by the lever 10 responsive to changes in temperature, as, for example, in a room the temperature of which is controlled through the medium of the burner apparatus.

45 In the starting of the burner it is preferred that the parts thereof supported on the base 17 be preliminarily heated, and this may be provided for in any desirable way, as for example by providing an annulus 31 of wicking in the basin portion 18 of the base, for impregnation with any suitable inflammable liquid.

50 The pipe 19 is provided for the purpose of conveying from the basin 18 any liquid hydrocarbon which may collect therein.

55 While I have illustrated and described a particular construction embodying my invention, I do not wish to be understood as intending to limit it thereto as the same may be variously modified and altered without departing from the spirit of the invention and the invention may be practiced by employing other forms of apparatus.

60 What I claim as new, and desire to secure by Letters Patents, is:

1. In combustion apparatus, the combination of a pump, means for causing liquid hydrocarbon and a carbureting material, to enter said pump, and a conduit through which the mixture passes from the pump to the point at which it is to be ignited, said conduit containing an enlargement between its ends, forming an expansion chamber, and 65 a venturi.

2. In combustion apparatus, the combination of a pump, means for causing liquid hydrocarbon and a carbureting material to enter said pump, and a conduit through which the mixture passes from the pump to the point at which it is to be ignited, said conduit containing an enlargement between its ends, forming an expansion chamber, and 70 a venturi opening into said enlargement.

3. In combustion apparatus, the combination of a pump, means for causing liquid hydrocarbon and a carbureting material to enter said pump, and a conduit through which the mixture passes from the pump to the point at which it is to be ignited, said conduit containing an enlargement, forming an expansion chamber with its bottom wall containing a recess, and an upwardly-extending venturi with its lower end disposed 75 at said recess.

100 JACK W. JOHNSON.
